CLOTHESLINE REEL

William John Thrower, Chester, W. Va.

Application February 16, 1945, Serial No. 578,192

1 Claim. (Cl. 242—100)

1
This invention relates to clothesline reels. An object of the invention is the provision of a reel having a base member adapted to be removably attached to the wall of a building with an axle projecting rigidly from the base member, with the axle being received by a passage in a rectangularly shaped body portion, the passage being adjacent one horizontal edge of the body, the body adjacent the opposite edge having a passage to receive a locking pin adapted to engage any one of a plurality of pockets formed in the base member, said pin being spring pressed to urge the pin in a pocket except when a head on the pin is in engagement with the outer edge of a boss on a flange secured to the outer end of the body, a second flange being secured to the opposite end of the body adjacent the base member and having passages to receive the axle and the pin.

Another object of the invention is the provision of a clothesline reel having an axle upon which is rotatably mounted a flat body, said body having a passage to receive a slidably mounted pin adapted to engage one of a series of pockets formed in the base member and retaining the body against rotation after a line has been wound thereon, a flange secured to the outer end of the base member and provided with diametrically disposed handles for manually rotating the body member for winding the line thereon.

A further object of the invention is the provision of a clothesline reel having a base member adapted to be removably secured to the wall of a building with a reel rotatably mounted on the base member and projecting laterally therefrom, said reel being composed of a flat body member upon which a line is adapted to be wound, with handles projecting from the body for manually rotating said body, means being employed for retaining the rotatable body against movement.

This invention will be best understood from a consideration of the following detailed description, in view of the accompanying drawings forming a part of the specification; nevertheless, it is to be understood that the invention is not confined to the disclosures, being susceptible of such changes and modifications as define no material departure from the salient features of the invention as expressed in the appended claims.

In the drawings:

Fig. 1 is an end view in elevation of a reel constructed according to the principles of my invention.

Fig. 2 is a side view in elevation of the same shown attached to the wall of a building.

2
Fig. 3 is a vertical section taken along the line 3—3 of Fig. 1.

Fig. 4 is an enlarged fragmentary vertical section through the reel and associated parts.

Referring more particularly to the drawings 10 designates the wall of a building to which is removably attached a base member 11 forming part of the reel. The upper end of the base member, as shown at 12 is cut away to receive a U-shaped member 13 which is secured at 14 to the building. The opposite end of the base member is provided with a slot 20 to receive a U-shaped member 21 which has sharp prongs 22 so that it may be driven into the wall of the building. The outer end of the U-shaped member projects beyond the outer face of the base member 11 and a pin 23 received by the U-shaped member 21 retains the lower end of the base member in position.

The pin has a head 24 which rests upon the staple or U-shaped member 21 when the pin 23 is in position. A chain 25 is secured to the head 24 and to the base member 11 to prevent the loss of the pin from said base member.

It will be seen by this construction that the base member may be readily attached to the wall of the building by inserting the cut away portion 12 of the upper reduced end 26 of the base member within the U-shaped clip 13. The lower end of the base member is then forced against the wall so that the member 21 will pass through the slot 20 a sufficient distance to receive the pin 23.

An axle 30 has its inner end received within a passage 31 in the base member 11 and is either cemented or tacked thereto. This axle extends outwardly through a passage 32 within a body or hub 33 of the reel. The body is substantially rectangular in shape and is considerably greater in width than it is in thickness. The upper and lower edges 34 and 35 respectively of the body are rounded and it is upon this substantially flat body that the rope 36 is wound as shown in Fig. 2 between the forward and rear flanges on the hub.

The forward flange 40 is provided with an elongated pocket 41 at its inner face and this pocket receives the outer end of the body 33. The outer end of the body may be cemented in the pocket 41 and a screw 42 secures the flange 40 to the outer end of said body. It will be noted from Figs. 1 and 2 that the flange 40 is provided with diametrically disposed hand grips 43 which are gripped by the operator for rotat-

ing the body 33 on the axle 30 for winding the rope 36 on said body.

The rear or inner flange 45 has a pocket 46 at its inner face which receives the inner end of the body 33. The inner end of the body is cemented within the pocket and also secured by a screw 47 to the flange 45. The flange 45 is similar in construction to the flange 40 and these two flanges, together with the body 33, form the reel per se.

A plate or washer 48 is located between the base member 11 and the flange 45 and is provided with an opening 49 through which passes the axle 30.

A washer 50 is received by the outer end of the axle 30 and is in flat contact with the outer flange 40. The collar 51 is mounted on the extreme outer end of the axle and is removably attached to the outer end by means of a pin 52 which is inserted within aligned passages within the axle 30 and the collar 51. By the removal of the pin, the collar 51 and the washer 50, the reel may be slipped off the axle.

The body member 33 adjacent the lower horizontal edge 35 is provided with a passage 53 in which is mounted a pin 54. The pin has a relatively smaller diameter than the passage 30 to accommodate a coil spring 54a which has one end in engagement with a plug 55 secured to the inner end of the pin. The outer end of the pin is provided with a manipulating handle 56.

A boss 57 has a central opening to receive the pin 54 and is secured to the outer face of the flange 40. The outer face of the boss is provided with a notch 60 to receive the circular enlargement or manipulating handle 56. Since the spring 54a is located between the boss 57 and the plug 55 it will force the plug toward the base 11 and into a pocket 61 when the member 56 is received within the notch or recess 60. On the other hand when the handle 56 is disposed at right angles to the plane of the notch 60 it will be seated upon the extreme outer edge of the boss against the tension of the spring 54a and maintain the plug 55 outwardly from the pocket 61 so that the reel may be freely revolved.

It will be noted from Figs. 1 and 4 that a plurality of pockets 61 are arranged circumferentially around the axle 30 so that the plug 55 may enter any one of said pockets when necessary. The plug 55 is held in position on the inner end of the pin 54 by a nut 62 threaded on to the extreme inner end of the pin. However, the pin 54 and plug 55 may be formed integrally.

It will also be appreciated that the reel composed of the body 33 and flanges 40 and 45 may likewise be formed integrally and the reel may be formed of wood, metal or plastic.

The operation of my device is as follows: The members 13 and 20 are secured to the

side of a building in spaced relation so that the reduced upper end of the base member 11 may be inserted within the U-shaped member 13 while the slot 20 may be received by the free end of the staple 21, after which the pin 23 is placed in position as shown in Figs. 1 and 2. After one end of the clothesline has been connected to a hook remotely from the reel and the other end of the clothesline is attached to the body 33 in any approved manner the reel may be rotated by manipulating the handles 43 after the pin 54 has been retracted to the position shown in Fig. 4. Rotation of the reel is continued until the line is sufficiently taut after which the handle 56 shown in Fig. 4 is moved to a right angular position shown in Fig. 3, whence the handle will be free to move into the notch 60 by the action of the spring 54a and the plug or plunger 55 will then be in engagement with the outer face of the base member 11. The reel is then rotated sufficiently to permit the plunger 55 to drop into one of the circumferential pockets 61 and thereby retain the reel against rotation and hold the line 36 taut.

It will be further noted that the reel may be readily disassembled when desired by the removal of the pin 52, the collar 51 and the washer 50. The entire assembly of the reel may then be slid off the axle 30 carrying with it the pin 54 and the plunger 55.

I claim:

A clothesline reel comprising a base having narrow end portions for attachment to a stationary support and an axle disposed thereon and extending outwardly therefrom, the face of said base having indentations arranged around the axle, a reel hub journaled on the axle having an inner flange and an outer flange having diametrically disposed extensions forming operating handles, said hub and flanges being provided with a through passage parallel to the axis, a spring pressed plunger in said passage cooperating with said indentations for locking the reel in different positions, a retracting rod on the plunger having a head extending beyond the outer flange and a cam boss on the latter with which said head may be engaged to hold the plunger in retracted position.

WILLIAM JOHN THROWER.
